UNITED STATES PATENT OFFICE.

THOMAS L. TITUS, OF OMAHA, NEBRASKA, ASSIGNOR TO THE TITUS MANUFACTURING COMPANY, OF OMAHA, NEBRASKA, A CORPORATION.

FLUSH VALVE.

1,412,905.

Specification of Letters Patent. Patented Apr. 18, 1922.

Application filed October 27, 1920. Serial No. 419,867.

To all whom it may concern:

Be it known that I, THOMAS L. TITUS, a citizen of the United States, residing at Omaha, in the county of Douglas and State 5 of Nebraska, have invented certain new and useful Improvements in a Flush Valve, of which the following is a specification.

This invention relates to a flushing device of the type employing a liquid receptacle for its main valve to modify its movements to its seat, and has for its objects to provide such a construction that the parts may be conveniently assembled, may be economically manufactured, and will be durable. The invention briefly includes a stationary, apertured supporting-tube provided with a needle valve and an expanding-disc and having a part disposed in the liquid receptacle, a cylindrical bearing-block slidably 20 mounted on the tube, a flexible ring between and normally engaging the bearing-block and expanding-disc, and a spring permitting disengagement of the ring from the disc while the main valve is moving from its 25 seat but which, in connection with the force of water pressure, will cause engagement of the ring with the disc and wall of the main valve while the latter is moving to its seat, whereby this last movement of the valve will 30 be subject to the flow of liquid through the needle valve of the supporting-tube.

In the accompanying drawing, Fig. 1 is a view of the device in longitudinal section. Fig. 2 is a side view of a supporting-tube 35 tension, and Fig. 3 is a view of the same in longitudinal section. Fig. 4 is a broken away view of the device, partly in section, showing position of the main valve while completing its movement from its seat. Fig. 5 is a plan view of the flexible ring or 40 washer. Fig. 6 is a side view showing a part of the supporting-tube. Fig. 7 is a sectional view on line 7—7 of Fig. 5. Fig. 8 is a sectional view, and Fig. 9 is a plan view 45 of the cylindrical bearing-block.

Referring now to the drawing, numeral 1 indicates a valve housing having a compartment 2 through which water under pressure may pass from its intake port 3 to its discharge port 4 by passing the valve seat 5, said housing having a compartment 6 communicating with said intake port and in communication with said discharge port subject to the control of a relief valve 7 disposed in a passageway 8 which communi-

cates with the compartment 6, said valve 7 normally being disposed upon a valve seat 9, adjacent to said discharge port 4.

In order that the objects first mentioned may be attained, I provide a supporting-tube 10 suitably secured to the top and extending within the valve housing, centrally on the valve seat 5. Numeral 11 indicates an extension for the tube 10, said extension having an aperture *a* formed longitudinally 60 therein, and preferably having a threaded connection for its inner end with said tube, its lower end being provided with a flange *b* for the support of one end of a spring 12, the upper end of said extension 11 being provided with an inwardly convergent recess or valve seat 13 for a needle valve 14 which is disposed in the tube 10 and which may be adjusted longitudinally of said tube, since its upper end has a threaded connection with 65 said tube, as best shown in Fig. 1, said needle valve being for the purpose of controlling the flow of water through the aperture *a* of said extension 11.

The tube 10 is also provided with an annular boss or disc 15, this being formed on its lower end adjacent to its threaded connection with the extension 11 and operating as a valve and also operating as an expanding element since its lower wall *d* is formed 70 downwardly convergent, as best shown in Fig. 6.

Numeral 16 indicates a main valve formed as a cylindrical receptacle, adapted to contain the tube-extension mentioned, its open, 75 upper end being provided with a flexible, annular cap 17 for a bearing upon the valve seat 5, said member 17 being secured to the top of the valve by means of a lock-nut 18. At 19 is indicated a cylindrical bearing-block 80 which is disposed within the cylindrical receptacle or main valve 16, whereby a lower compartment *x* and an upper compartment *x'* are provided for said receptacle, said block 19 being in constant engagement with the upper end of the spring 12, and having apertures *e* formed longitudinally therein and having a central aperture for a slidable mounting on the tube-extension 11. Numeral 20 indicates a flexible ring or washer disposed between the valve 15 and the cylindrical block 19 and which constantly engages and is supported by said block. 85

In operation, the parts being disposed as 90

2
shown in Fig. 1, if the valve 7 is moved from its seat 9, handle 21 being used for this purpose, water will move through the passageway 8 from the compartment 6, and will 5 move from the intake 3 to the compartment 6 through the annular passageway 22, with the result that the main valve 16 will immediately leave its seat 5, this movement of the valve 16 being subject to the action of 10 the spring 12 upon the bearing-block 19, and the tendency to form a vacuum in the compartment α will cause the block 19 to move a limited distance inwardly of compartment α , the ring 20 also moving with 15 said block and forming an annular passageway p , as shown in Fig. 4, between said member 20 and member 15, through which water will readily pass to the compartment α by moving through the passageways e , 20 the proportion of parts being such that flushing may be quickly accomplished.

On account of the described construction, the movement of the valve 16 to its seat, after the valve 7 has been closed, will not be 25 attended by appreciable vibration. A slide-able movement of the valve 16 on the block 19 and ring 20 toward its seat 5 occasioned by water pressure and aided materially by pressure of the spring against said block, 30 will cause immediate engagement of the ring 20 with member 15, which will prevent water from moving out of the compartment α through the apertures e , and therefore the water will move from said compartment α 35 to the compartment α' by passing through the aperture a of the extension 11 and through certain apertures 23 of the tube 10, subject to the control of the needle valve 14.

It will be noted that the ring 20, on account 40 of the convergent wall d of member 15, will be pressed outwardly against the wall of the receptacle 16 as well as against said wall d , which will operate to great advantage while the valve 16 is moving to its 45 seat since it makes an effective closure of the valve 15 upon its seat 20, and since the aperture a is the only passageway through which water may pass during this movement of the valve 16, the degree of speed 50 for the latter may be effectively controlled by the needle valve.

It will be noted that the parts required for the device are few and simple and may be conveniently manufactured at, comparatively, a very limited cost, and may be readily assembled. The operation of the valve 55 is practically noiseless, and on account of the adjustable features mentioned, the closing of the main valve 16 may be more or less rapid, as may be required.

Numerals 24 indicates a stop-pin for limiting the movement of the main valve in one direction, said pin being threaded in a packing nut 25 at the lower part of the valve 60 housing.

It will be noted that the screw-head for the stem of the needle valve makes a closure of the bore of the tube 10, and while this tube has been specifically mentioned, any other support may be substituted which provides an adjustable mounting for the needle valve, and which permits water to move to compartment 2 from the aperture a when the valve 16 is moving to its seat. Also it will be noted that the diameter of the disc 75 15 should be less than that of the bore of said valve to form an annular recess or passageway m therebetween and thereby to permit water to pass through the passageway p when the valve 16 is moving from 80 its seat.

It is considered that the apertures e for the block 19 may be dispensed with if the fitting of this block is sufficiently loose on the extension 11 but an apertured block is 85 preferred so that water may pass quickly and without undue resistance to the compartment α when the valve 16 moves from its seat. While the construction, substantially as described, is preferred, it will be 90 understood, of course, that changes in size, form, proportion, and minor details may be made, said changes to be determined by the scope of the invention as claimed.

I claim:

1. In combination, a valve housing having a valve seat between its intake and discharge ports, an apertured supporting-tube provided with an expanding-disc and secured to the housing to extend through the valve seat to the pressure side thereof, a bearing-block loosely mounted on the tube, a flexible ring encircling the tube between the bearing-block and disc normally engaging said block, resilient means for causing normal engagement of the flexible ring with said disc, a cylindrical receptacle circumscribing the bearing-block, the flexible ring, the expanding-disc and normally engaging the valve seat and flexible ring, and a relief 100 valve movable for causing the movement of the cylindrical receptacle from its seat and disengagement of the flexible ring from the expansion disc.

2. In combination, a valve housing having 115 a valve seat between its intake and discharge ports, an apertured supporting-tube provided between its ends with an expanding-disc, said tube being secured to the housing and extending through to the pressure side 120 of said valve seat, a cylindrical, longitudinally apertured bearing-block loosely mounted on the supporting-tube, a flexible ring encircling the tube between the bearing-block and expanding-disc normally engaging said block, a spring carried by said tube engaging the bearing-block for causing normal engagement of the flexible ring with said disc, a cylindrical receptacle circumscribing the bearing-block, the flexible ring, the expand- 125 130

ing-disc and normally engaging the valve seat and flexible ring, and a relief valve movable for causing the movement of the cylindrical receptacle from its seat and disengagement of the flexible ring from the expanding-disc.

3. In combination with a valve housing having a valve seat between its intake and discharge ports, of an apertured supporting-tube provided between its ends with an expansion-disc and a valve seat, said tube being secured to the housing and extending through to the pressure side of said valve seat, a cylindrical, longitudinally apertured bearing-block loosely mounted on the supporting-tube, a flexible ring encircling the tube between the bearing-block and expansion-disc normally engaging said block, resilient means for causing normal engagement of the flexible ring with said disc, a needle valve having a part disposed adjacent to the valve seat of the supporting-tube and having a part closing the bore of said tube, a cylindrical receptacle circumscribing the bearing-block, the flexible-ring, the expansion-disc and normally engaging the flexible ring and first named valve seat, and a relief valve movable for causing the movement of the cylindrical receptacle from its seat and disengagement of the flexible ring from the expansion-disc.

4. In combination with a valve housing having a valve seat between its intake and discharge ports, of an apertured supporting-tube provided between its ends with an expansion-disc and a valve seat, said tube being secured to the housing and extending through to the pressure side of said valve seat, a cylindrical, longitudinally apertured bearing-block loosely mounted on the supporting-tube, a flexible ring encircling the tube between the bearing-block and expansion-disc normally engaging said block, a spring carried by said tube in constant engagement with the bearing-block for causing normal engagement of the flexible ring with said disc, a needle valve having a part disposed adjacent to the valve seat of the tube and having a part closing the bore of said tube, a cylindrical receptacle circumscribing the bearing-block, the flexible ring, the expansion-disc and normally engaging the flexible ring and first named valve seat, and a relief valve movable for causing the movement of the cylindrical receptacle from its

seat and disengagement of the flexible ring from the expansion-disc.

5. In combination, a valve having a valve seat between its intake and discharge ports, an apertured supporting-tube provided with an expansion disc having a convergent wall 60 and secured to the housing to extend through the valve seat to the pressure side thereof, a bearing-block loosely mounted on the tube, a flexible ring encircling the tube between the bearing-block and disk normally engaging said block, resilient means for causing normal engagement of the flexible ring with the convergent wall of said disc, a cylindrical receptacle circumscribing the bearing-block, 70 the flexible ring, the expansion-disc and normally engaging the valve seat and flexible ring, and a relief valve movable for causing the movement of the cylindrical receptacle from its seat and disengagement of the flexible ring from the expansion disc, said disc having a lesser diameter than the bore of said receptacle, to provide a passageway.

6. In combination, a valve housing having a valve seat between its intake and discharge ports, an apertured supporting-tube provided between its ends with an expansion-disc having a convergent wall, said tube being secured to the housing and extending through to the pressure side of said valve seat, a cylindrical, longitudinally apertured bearing-block loosely mounted on the supporting-tube, a flexible ring encircling the tube between the bearing-block and expansion-disc normally engaging said block, a 90 spring carried by said tube engaging the bearing-block for causing normal engagement of the flexible ring with the convergent wall of said disc, a cylindrical receptacle circumscribing the bearing-block, the flexible 95 ring, the expansion-disc and normally engaging the valve seat and flexible ring, and a relief valve movable for causing the movement of the cylindrical receptacle from its seat and disengagement of the flexible ring 100 from the expanding-disc, said disc having a lesser diameter than the bore of said receptacle to provide a passageway.

In testimony whereof, I have affixed my signature in presence of two witnesses.

THOMAS L. TITUS.
